UNITED STATES PATENT OFFICE

HENRY E. KONDOFF, OF BROOKLYN, NEW YORK

FOLDED PAPER PACKAGE

Application filed December 28, 1925. Serial No. 78,020.

My present invention relates to an improvement in folded paper packages or cartons, and the principal object thereof is to provide an improved paper package in which a commodity may be dispensed, together with a refrigerant for keeping the temperature of the commodity low, the construction being such that the commodity is retained within insulated walls to thereby confine the action of the refrigerant to the preservation of the commodity, and thus increase the efficiency of the package.

A further object of my invention is to provide a package of the type set out above, which may be sealed against opening, and which requires mutilation of the package to gain access to its contents, to thereby insure against tampering with the contents of the package en route, and against reuse of the package.

Another object of the invention is to so construct the package that it may be shipped in folded form, to thereby occupy minimum space, the package being so made that it may readily be extended to position for receiving its contents.

With these and other objects in view, which will become apparent as the description proceeds, the invention resides in the construction, combination and arrangement of parts hereinafter more fully described and claimed.

In the drawings.—

Figure 1 represents a plan view of the blank from which the cover of the package or box is formed.

Figure 2 represents a plan view of the blank from which the body of the package or box is formed.

Figure 3 represents a plan view of the box body formed, and folded into flat position from the position indicated in Figure 5, to thereby minimize the space occupied by the formed box body.

Figure 4 represents a view in perspective of the cover in its process of formation from the blank shown in Figure 1.

Figure 5 represents a view in perspective of the box body in an intermediate position from the flat folded position of Figure 3 to the fully extended position of Figure 6.

Figure 6 represents a view in perspective of the box body extended.

Figure 7 represents a perspective view of the box body and cover, the body having the end flaps (shown extended in Figure 6), folded in, the body being in position to receive its contents, and the cover being illustrated in a position ready to be placed upon the body.

Figure 8 represents a view in perspective of the package when completed.

Figure 9 represents a view in perspective of the package ready for transportation, it being noted that the position of the package in Figure 9 is upside down with respect to the position shown in Figure 8, i. e., the top surface of the package in Figure 8 becomes its bottom surface in Figure 9, and the bottom surface in Figure 8 becomes the top surface in Figure 9.

Figure 10 represents a longitudinal sectional view taken along the line 10—10 of Figure 9.

Figure 11 represents a transverse sectional view along the line 11—11 of Figure 9, and

Figure 12 represents a transverse sectional view along the line 12—12 of Figure 9.

Referring more particularly to the drawings, the blank from which the cover is formed, is made up of what is known as corrugated material, it consisting of sheets separated by a corrugated partition serpentine in cross section. Such corrugated material is well known, and serves admirably the purpose of insulation, desirable in my present package. The cover blank includes the cover section 5, the side wall sections 6, which flank the cover section, and which are separated therefrom along the scores 7, and end wall sections 8, which form continuations of the cover section 5, and are separated therefrom along the scores 9.

The end wall sections are flanked by side insert strip sections 10, separated from the end wall sections along the scores 11, which form continuations of the score 7, and the insert strip sections 10 are separated by cuts 12 from the side wall sec-

tions 6. End insert strip sections 13 are separated from the ends of the end wall sections 8 along creases 14.

The blank, illustrated in Figure 2, from

which the body of the box is to be formed, is made of paper of the desirable thickness, it not being necessary to form this portion of the package of the corrugated and insulating material. Such box body blank includes the bottom section B, flanked by side sections 16 which are separated from the bottom section along scores 17. Each of the side sections are continued to form partition wall sections 18, separated from the side sections along the creases 19. The partition wall sections of one of the side sections 16 falls into the portions or divisions 20 and 21, separated along the scores 23, while the partition wall sections of the other side section falls into three parts 24, 25, and 26, respectively, the parts 25 being separated from the parts 24 and 26 along the scores 27 and 28, respectively.

Forming continuations of the bottom section B, are the end flap sections 30, separated from the bottom section along the scores 31. The end flap sections are separated from the partition wall sections by the cuts 32, and it will be noted that these cuts are of a sufficient width that when the side sections 16 are folded up along the creases 17, the then lower edges of the partition wall sections will be above the bottom section a distance substantially equal to the thickness of the corrugated material of which the cover is formed, and similarly the ends of the end flap sections will be spaced inwardly from the sides 16 a distance substantially equal to twice the thickness of the material forming the cover.

The bottom section B is perforated as at 33, to form a multilatable lid 34, which may hinge upwardly along one of the creases 17, it being necessary, however, before such lid section can be thus moved, to separate it from the bottom section B along the lines of perforations 33. Opposite the crease or score 17, along which the lid hinges, the lines of perforations merge into a semi-circular cut 35, which forms a tab 36, which may be raised to initiate the separation of the lid from the bottom section.

The bottom section is longitudinally and centrally scored (i. e., transversely of the blank) along the line 37, and the end flap sections 30 are scored along continuations 38 of the score 37, so that the halves of the bottom section will fold upon themselves when the blank is in the formed and folded position of Figure 3, and the halves of the end flap sections may likewise fold upon themselves as therein indicated.

The cover sections are ordinarily shipped from the manufacturer to the user in the blank form shown in Figure 1, to be formed into the cover by the user. The box sections may also be shipped in the blank form, but inasmuch as it is necessary to glue together certain portions of the box section, before the box is ready for use, the box section is preferably formed and folded at the factory, and

shipped to the customer in its formed and folded position indicated in Figure 3. This position is obtained by bending up the side sections 16 of the box blank along the scores 17. Then the partition walls may be formed, by bending the parts or hinge sections 20 of the partition wall sections of one side 16 inwardly along the scores 19, and the parts or hinge sections 24 of the other side section inwardly along the scores 19, then over-lapping the parts 21 of the partition wall sections of the first side with the parts 26 of the partition wall sections of the other side, as indicated in Figure 5, the parts 21 and 26 being glued together. The scores 28, dividing the parts 26 from the parts 25 of the partition wall sections of one side, thus occupy a central position in the vertical plane of the score 37 of the bottom, midway between the sides 16 of the box body. The parts 20 and 24, respectively, thus form hinge sections which dispose the partition walls A comprising the parts 21, 26, and 25) inwardly of the ends of the box body. From the position of Figure 5, the box may be compressed to the flat condition of Figure 3, the partitions folding upon themselves along the scores 28, and the bottom and end flap sections folding upon themselves along the scores 37 and 38, respectively.

When a package is to be used, the formed and folded box body is transposed from the position of Figure 3 to that of Figure 6, by pulling the sides out to partially extend the partition walls and the bottom and the end flaps, as indicated in Figure 5, then pressing down on the box to flatten the bottom and end flaps, and then pulling the partitions out to the extended position of Figure 6. An insulating blank 39 (see Figures 6, 10, 11 and 12) is then inserted in the body portion of the box, being slipped in on top of the bottom B and engaging between it and the lower edges of the partitions A. Such blank may be made from the same material as that from which the cover is formed, and in width, substantially equals the width of the bottom B. In length the insulating blank is preferably slightly longer than the distance between the partitions A in the extended box, and may be slightly longer than the multilatable lid 34. The body portion of the box is now completed by folding up the end sections 30 along the scores 31, thus taking the condition indicated in Figure 7, in which condition it is ready to receive the commodity, and its refrigerant.

It can here be noted that my present package may be used for dispensing commodities such as ice-cream, or crab meat, or shrimp, or other like commodities which preferably are kept cool. The central space of the box receives such commodity. The refrigerant that may be used, it is anticipated, may take the form of blocks of what is known as dry

ice. The end compartments, i. e., the spaces beyond the partitions, are to receive this refrigerant. It is possible that ice may also be used as a refrigerant.

5 The cover is formed from the blank condition of Figure 1 to that of Figure 7, by folding the side wall sections 6 up along the scores 7, and similarly folding the side insert strips 10 upwardly along the scores 11 and 10 the end insert strips 13 upwardly along the scores 14. The end wall sections, carrying their insert strips 10 and 13, may then be folded inwardly along the scores 9, as indicated in Figure 4. The cover is then turned 15 upside down and the end wall sections pulled outwardly to take the position indicated in Figure 7.

The box having been packed with its commodity and refrigerant, the cover is then 20 placed upon the box, by slipping the wall sections 6 into the box section between the sides 16 thereof and hinge sections 20 and 24, and by then sliding the cover down until its 25 lower edges rest against the insulating blank 39, adjacent the edges of the latter. The end wall sections of the cover are then folded in to take the position indicated in Figure 8, the side insert strips 10 slipping in against the inner faces of the hinge sections 20 and 30 24, thereby locking them against the side wall sections 6 of the cover, and the end insert strips 13 slipping in against the upper faces of the end flap sections 30, thereby locking such end flap sections against the 35 outer faces of the partitions and against the end edges of the insulating blank 39 (see Figure 10, in which the package is upside down with reference to Figures 7 and 8, i. e., in position for carrying).

40 The box may then be sealed, if desired, by bridging one or both of the upper edges of the side 16 of the box body with the upper surface of the cover by means of a sealing strip 40, as indicated in dotted lines in Figure 8. Also if desired, a sealing strip may be 45 run around the end edges of the box and cover, or either one of these methods may be used. Preferably, however, I seal the package, and retain it proof against access, save 50 by mutilation, by the use of a continuous cord 41, which, at its ends, is provided with anchors 42 disposed on the inside of the end compartments, as indicated in Figure 10. To this end the bottom section B, adjacent its 55 ends; the end flap sections 30, and the insert strip sections 13, are provided with small perforations 43, which, when the package is completely formed and filled, as indicated in Figure 8, register with each other. In order to fasten the cord, the package is turned upside down from the completed position of Figure 8, to the position of Figure 9, the anchor 42 at one end of the cord being then 60 inserted through the registering perforations

43 at one end of the box and the cord being drawn along the outside of the box and the anchor at the other end of the cord being similarly inserted through the registering perforations near the other end of the box. 70 These anchors having been inserted, cannot be removed without mutilating the cord or the box. At the same time, there is just sufficient slack in the cord for it to form a handle whereby the box may be conveniently 75 carried. The reversal of the box thus brings its bottom uppermost and its top lowermost, and brings the lid 34 onto the top of the box. When the box has been delivered and is ready for opening, the cord may be snipped, the finger inserted under the tab 36, to initiate the separation of the lid from the box, and then the lid may be folded upwardly, being drawn away from the bottom along the line of perforations. This operation exposes the 80 insulating blank 39, and this blank may then be removed, to give access to the contents of the package.

It will be observed that during this operation of gaining access to the package, the compartments at the ends of the package which contain the refrigerant are left undisturbed, it being unnecessary to handle the refrigerant at all, so that no soiling of the hands, or the use of implements in the removal of a 95 refrigerant before the contents are available, is necessitated. It will be noted that the package may not again be used, without knowledge of its prior use being conveyed by the mutilation of the package, and it is 100 also noteworthy that the package is proof against access, without mutilation, once the sealing strips or the sealing cord have been applied.

It is further of interest to note that the 105 package (being in condition for delivery, as indicated in Figure 10), has an insulated wall at its bottom formed by the top of the former cover, insulated walls at its sides formed by the sides of the former cover, 110 an insulated wall at its top, formed in part by insulating blank 39, and in remainder by the end insert strips 13, and has insulated walls at its ends, formed by the end wall sections 8. Hence the action of the refrigerant will be confined, in high degree, to the interior of the package. It is also noteworthy that the insulating blank will be retained in place by the partition walls and by the over-lapping edges of the end flaps 115 30, and that these end flaps also act to lock the partition walls in position.

The foregoing detailed description has been given for purposes of illustration, and no 120 undue limitations should be deduced therefrom, but the ensuing claims should be construed as broadly as permissible, in view of the prior art.

Having thus described my invention what 130

I claim as new and desire to secure by Letters Patent is:—

1. A paper container comprising a body section, and a separate cover section, the body section having side walls and having partitions inset from the ends of the side walls and connected to the side walls by hinge sections, an insulating blank inserted between the bottom of the body section and the adjacent edges of the partition walls, said bottom having end flaps folded against the end edges of the insulating blank and bearing against the partition walls to thereby lock said insulating blank and partition walls in place, said cover section being formed of insulating material and having side walls inserted between the said hinge sections and the sides of the body section, and having end sections spaced from the partition walls and provided with insert flaps bearing against said hinge sections and with insert flaps bearing against said end flaps.

2. A paper container comprising a body section, and a separate cover section, the body section having side walls and having partitions inset from the ends of the side walls, hinge sections connecting the partitions to the sides of the body section, an insulating blank inserted between the bottom of the body section and the adjacent edges of the partition walls, said bottom having end flaps folded against the end edges of the insulating blank and bearing against the partition walls to thereby lock said insulating blank and partition walls in place, said cover section having side walls inserted between the said hinge sections and the sides of the body section, and having end sections spaced from the partition walls and provided with insert flaps bearing against said hinge sections and with insert flaps bearing against said end flaps, and a locking cord passing through registering perforations in the body section, end flap, and last said insert sections, and having its ends anchored within the container.

3. A paper container comprising a body section and a separate cover section, said cover section being formed of insulating material, the body section having partition walls inset from the ends thereof, hinge sections connecting the partition walls to the body walls, and flaps engaging the partition walls for locking them in place, said cover section having side walls adapted to slidably fit between the body walls and said hinge sections and having end sections adapted to be engaged in the ends of the body section in spaced relation to the partition walls to thereby close the ends of the body section, and being provided with insert flaps adapted to bear against the hinge sections and end flaps.

4. A paper container comprising a body section, and a separate cover section, the body section having side walls and having partitions inset from the ends of the side walls, an

insulating blank disposed between the bottom of the body section and the adjacent edges of the partition walls, said bottom having end flaps folded against the edges of the insulating blank and bearing against the partition walls to thereby lock said insulating blank and partition walls in place, said cover section having side walls inserted between the partition walls and the sides of the body section, and having end sections spaced from the partition walls and closing the ends of the body section.

5. A paper container comprising a body section, and a separate cover section, said cover section being formed of insulating material, said body section having partition walls inset from the ends thereof, an insulating blank inserted between the bottom of the body section and the adjacent edges of the partition walls, said insulating blank being shorter than the body section, said cover section having side walls engaging between the side walls of the body section and the partition walls, and having end sections closing the ends of the body section and spaced from the partition walls and provided with insert flaps arranged beyond the ends of the insulating blank to complete the insulation of the body section along the bottom thereof.

6. A paper container comprising a body section, and a separate cover section, said cover section being formed of insulating material, and slidably fitting the body section, an insulating blank disposed against a wall of the body section, and being shorter than such body section, said cover section being provided with end sections closing the ends of the body section and having insert flaps arranged beyond the ends of the insulating blank.

7. A paper container comprising a body section, and a separate cover section, said cover section being formed of insulating material slidably fitting the body section and having end sections closing the ends of the body section, an insulating blank arranged against one wall of the body section between the ends of the end sections, such wall being provided with a multilatable lid adapted to provide access to the package for the removal of the insulating blank.

8. A paper container comprising a body section having a central and end compartments separated by partition walls, a separate cover formed of insulating material and having a top wall covering the compartments and having side walls at the sides of the compartments, and end walls at the ends of the end compartments opposite the partition walls, and having insert flaps at the bottom of the end compartments, and an insulating blank covering the bottom of the central compartment between the insert flaps.

9. A paper container comprising a body section, a cover section formed of insulating

material and having portions forming insulating walls for the container, save for a space along one wall of the body, an insulating blank occupying such space, and a mutilatable lid in such wall over said blank.

5 10. A paper container comprising a body section having end flaps folded with respect to a wall thereof, a cover section having end walls provided with insert flaps arranged 10 against the end flaps, said end flaps, insert flaps and body wall having registering perforations, and a sealing cord extending through the perforations and having its end anchored within the container.

15 11. A paper container comprising a body section, a separate cover section engaging the body section and having end walls forming the ends of the container and provided with insert flaps, a cord anchored at its ends within 20 the container and extending through the insert flaps and through a wall of the body section, and a mutilatable lid in the body section under-lying the cord intermediate its ends.
